ATTORNEY

UNITED STATES PATENT OFFICE.

GUY L. WOODJARD, OF SAN DIEGO, CALIFORNIA.

PAPER AND PLASTER-FOUNDATION SUPPORTING DEVICE.

Application filed August 24, 1922. Serial No. 584,143.

To all whom it may concern:

Be it known that I, GUY L. WOODJARD, a citizen of the United States, residing at San Diego, in the county of San Diego and 5 State of California, have invented a certain new and useful Paper and Plaster-Foundation Supporting Device, of which the following is a specification.

My invention relates to a device for 10 securing building paper and supporting plaster foundation more particularly for spacing and supporting metallic netting from sheathing, studding or other wall structures principally for plastic wall construction and the objects of my invention are: First, to provide a device of this class which will reduce the cost of securing building paper and plaster foundation to wall structures and also greatly facilitate the 15 securing of the same; second, to provide a device of this class for securing building paper in position to a wall structure and at the same time provide efficient means for securing hog, chicken or other wire netting 20 or plaster foundation to the wall structure without the addition of other parts; third, to provide a device of this class which will space the plaster foundation from the walls as well as support the same thereon; fourth, 25 to provide novel means for supporting plaster foundation; fifth, to provide a novelly constructed device of this class and sixth, to provide a device of this class which is very simple and economical of construction, durable, efficient, easy to install and 30 will not readily deteriorate or get out of order.

With these and other objects in view as will appear hereinafter my invention 35 consists of certain novel features of construction combination and arrangement of parts and portions as will be hereinafter described in detail and particularly set forth in the appended claims, reference being had to the 40 accompanying drawings and to the characters of reference thereon which form a part of this application in which:

Figure 1 is a front elevational view of 45 my device showing the same supporting building paper in position to a wall structure and also supporting and spacing plaster foundation from the same; Fig. 2 is a side elevational view thereof showing by dotted lines the securing nail partially driven into 50 the wall structure and also showing by

dotted lines a securing means made an integral portion of the clip portion; Fig. 3 is another side elevation view thereof showing its partially distorted shape after being permanently secured to the wall structure; Fig. 4 is another side elevational view thereof showing a means of retaining the nail in the supporting clip member; Fig. 5 is a slightly modified form of construction of 55 my device with a portion of the clip member omitted; Fig. 6 is a front elevational view of another slightly modified form of construction of my device from that shown in Fig. 5 except that an additional outwardly extending hook portion is provided showing the hook portion supporting and spacing plaster foundation from the wall structure; Fig. 7 is a side elevational view thereof; Fig. 8 is a front elevational view of another 60 slightly modified form of construction of my device showing the same securing building paper and plaster foundation to a wall structure; Fig. 9 is a sectional elevational view thereof taken through 9—9 of Fig. 8; Fig. 10 is another sectional view thereof taken through 10—10 of Fig. 9; Fig. 11 is a sectional elevational view of another slightly modified form of construction of my device showing the same supporting building paper and plaster foundation to a wall 65 structure and Fig. 12 is still another slightly modified form of construction of my device.

Like characters of reference refer to similar parts and portions throughout the 70 several views of the drawings.

The clip 1, and the nail 2 constitute the 75 principal parts and portions of my device for supporting weather paper and plaster foundation in the preferred forms of construction.

The clip member shown in Figs. 1 to 7 of the drawings is preferably made of semi-resilient sheet metal bent into a series of loops to provide flexibility and simple and efficient means for supporting and spacing the plaster foundation on and from the wall by the loop portion as shown best in the drawings. Figures 1 to 4 of the drawings show the clip member substantially in the 80 shape of a **W** while the clip member shown in Figs. 5 to 7 of the drawings show the same substantially in the shape of the letter **S**. It will be noted that the weather or 85 building paper is secured and supported 90

simultaneously to the securing and spacing of the plaster foundation to the wall structure. It will also be noted that the head of the nail is spaced inwardly or toward the supporting wall structure from the plane of the plaster foundation, so that said head will not interfere with the applying of the plastic material to the wall structure as shown best in Figs. 2, 3, 4, 5 and 7 of the drawings. The outermost loop portion 1^a of the S shaped clip member of my device as shown in Figs. 6 and 7 of the drawings is provided with an outwardly extending hook portion 1^b preferably made an integral portion of the said member to receive and secure the plaster foundation, which hook portion is bent inwardly by the head of the nail 2 as the same is driven into the wall structure in securing the clip member itself thereto.

The plaster foundation securing and spacing member in the modified form of construction as shown in Figs. 8, 9 and 10 of the drawings consists of a button 3 preferably moulded or pressed out of metal and is provided with a hook portion 3^a as previously described in connection with the plaster foundation securing member in Figs. 6 and 7 of the drawings. Said hook portion is similarly bent inwardly as the nail 2 is driven into the wall structure for securing the member 3.

The plaster foundation and securing member shown in Fig. 11 of the drawings consists of a solid block 4 with a transverse hole 4^a therethrough to receive the nail 2 and a groove 4^b contiguous to the hole 4^a on the outside face of said block 4 to receive a strand of the plaster foundation, said strand being secured by the head of the nail securing the block 4 to the wall structure.

The building paper securing and plaster foundation securing and spacing member as shown in the modified form of construction in Fig. 12 of the drawings consists of a nail 5 with two heads 5^a and 5^b, the latter head being spaced from and in alignment with the head 5^a. The head 5^b is provided with a slot portion 5^c in one side of said head and extends to the central portion thereof which slot is adapted to receive a strand of the plaster foundation. The member 5 is driven into the wall structure similarly to the conventional nail by driving on the extended head 5^b; the strand of plaster foundation is then inserted in the slot 5^c of the head 5^b and by a blow of the hammer on the side of the head provided with the

slotted portion, the plaster foundation is secured in place.

Though I have shown and described a particular construction, combination and arrangement of parts and portions and certain modifications thereof I do not wish to be limited to this particular construction, combination and arrangement nor to the modifications but desire to include in the scope of my invention the construction, combination and arrangement substantially as set forth in the appended claims.

It is obvious that the securing member may be made an integral portion of or interwoven with the strands of the plaster foundation if desired in order to reduce the cost and still further facilitate the securing of the plaster foundation to wall structures.

Having thus described my invention what I claim as new and desire to secure by Letters Patent is:

1. A device of the class described, including a yieldable plaster foundation supporting member formed with consecutive alternately disposed loop portions and a pointed securing member positioned at a substantial right angle to one side of said supporting member and extending therethrough adapted to secure said supporting member to a wall structure.

2. A device of the class described, including a plate, folded into consecutively spaced and alternately disposed resilient portions forming a plaster foundation securing and spacing portion at its outer end and a securing member extending through several of said folded, alternately disposed resilient portions into a supporting structure, positioning and locking said plaster foundation in the securing and spacing portion of said supporting member.

3. A device of the class described, including a plaster foundation supporting member provided with consecutively spaced and oppositely disposed, resilient, folded portions providing a plaster foundation securing and spacing portion at its outer end and a nail means extending through holes in several of said folded portions into a wall structure, positioning and clamping said plaster foundation in the securing and spacing portion of said supporting member with its head, which head is positioned nearer the wall structure than the plaster foundation.

In testimony whereof, I have hereunto set my hand at San Diego, California, this 16th day of August 1922.

GUY L. WOODJARD.
